UNITED STATES PATENT OFFICE.

LEONIDAS PETHOUD, OF BEATRICE, NEBRASKA.

FEED-GRINDER.

1,141,825.

Specification of Letters Patent.

Patented June 1, 1915.

Application filed November 26, 1913. Serial No. 803,312.

To all whom it may concern:

Be it known that I, LEONIDAS PETHOUD, a citizen of the United States, residing at Beatrice, in the county of Gage and State of Nebraska, have invented new and useful Improvements in Feed-Grinders, of which the following is a specification.

This invention relates to feed grinders and it consists in the novel features herein-
10 after described and claimed.

An object of the invention is to provide a grinder of simple structural arrangement which is adapted to efficiently reduce feed as for instance alfalfa, hay, corn, wheat, oats
15 and the like to small particles in order that the same may be prepared for stock feeding.

With the above object in view the grinder comprises a shaft from which is mounted a series of spaced saws. Bars are mounted on
20 a fixed support and project into the spaces between the saws the said bars are approximately radially disposed with relation to the saws. A plate is positioned adjacent the saws and is disposed at a tangent to a circle
25 struck from the center of the saws and the said plate is provided with teeth which project into the spaces between the saws. A bar is mounted under the said plate and extends transversely across the saws in close
30 proximity to the ends of the teeth thereof. The said bars and plate are of hard steel and may be mounted on suitable supports of any desired material.

In the accompanying drawings: Figure 1
35 is a side elevation of the grinder. Fig. 2 is a top plan view of the same. Fig. 3 is a vertical sectional view of the grinder. Fig. 4 is a perspective view of a plate used upon the grinder. Fig. 5 is a perspective view
40 of a tooth used upon the grinder. Fig. 6 is a side elevation of a modified form of arrangement of the parts of the grinder.

As illustrated in the drawing the grinder comprises a frame 1 upon which is journaled
45 a shaft 2. Any suitable means may be provided for rotating the shaft. Saws 3 are keyed upon the shaft 2 and are held in spaced relation with respect to each other by means of disks 4 which are interposed be-
50 tween the saws and which are also keyed upon the shaft. The sides of the saws are in close contact with the sides of the disks throughout the series of saws and disks.

Bars 5 of hard steel are mounted upon the
55 frame 1 at one side of the series of saws and the said bars are provided with pointed ends

6 which project into the spaces between the saws and which terminate in close proximity to the peripheries of the disks 4. A block 7 is mounted over the bars 5 and a plate 8 is attached to the said block. The said plate lies in a plane which is disposed at a tangent to a circle struck from the centers of the saws. The plate 8 is provided at its lower edge with teeth 9 which project into the spaces between the saws. The said plate is made from hard steel. A bar 10 is attached to the block 7 and lies under the lower portion of the plate 8 and teeth 9 thereof. The said bar is also of hard steel and extends
65 transversely across the series of saws 3 and its inner surface is in close proximity to the ends of the teeth of the said saws. A hopper 11 of any desired form may be positioned upon the frame 1 over the upper portions of the saws and the block 7 and plate 8.
70

The material to be ground is deposited on the hopper 11 and the shaft 2 is rotated. Thus the teeth of the saws 3 touch the said material and carry it toward the plate 8. At the edges of the teeth 9 of the said plate the said material is cut into bits which may be as large or smaller than the spaces between the adjacent teeth of the saws 3. This cut material is carried down by the teeth of the saws and when the teeth are below the centers of the saws the said material falls from the teeth into any suitable receptacle provided for its reception. Therefore it will be seen that a grinder of simple structure is provided for reducing feed material to small particles. If desired the plate 8 and block 7 may be dispensed with and in this instance a second set of bars 5 is positioned adjacent the opposite sides of the saws from the first mentioned set of bars and the last mentioned set of bars will direct the material onto the saws and will remove any particles of the material from between the saws which may be carried around the 95 saws from the first mentioned set of bars.
100

Having described the invention what is claimed is:—

A grinder comprising a frame, a shaft journaled upon the frame, a set of saws fixed to the shaft, a set of disks fixed to the shaft and interposed between the saws and maintaining the saws in spaced relation, a set of bars fixed to the frame and having end portions which project into the spaces between the saws and which terminate in close proximity to the peripheries of the 110

disks, a block mounted upon the frame above the bars, a plate mounted upon the block and having at its lower edge teeth which project into the spaces between the bars and which rest against the upper edges of the said bars, the said plate being disposed at a tangent to a circle struck from the center of the saws and the upper surfaces of the teeth disposed at an angle to the upper surface of the body of the plate, and a bar mounted upon the block beneath the plate and the teeth thereof and having

a surface in close proximity to the ends of the saws and which bridges the spaces between the teeth of the plate, the lower edge 15 of the last mentioned bar resting upon the upper edges of the first mentioned bars.

In testimony whereof I affix my signature in presence of two witnesses.

LEONIDAS PETHOUD.
